Smith & Denison

UNITED STATES PATENT OFFICE.

ROBERT I. TURCK, OF GENEVA, NEW YORK, ASSIGNOR OF ONE-HALF TO
GEORGE A. FITTON, OF SAME PLACE.

SASH-FASTENER.

SPECIFICATION forming part of Letters Patent No. 432,004, dated July 8, 1890.

Application filed February 20, 1890. Serial No. 341,095. (No model.)

To all whom it may concern:

Be it known that I, ROBERT I. TURCK, of Geneva, in the county of Ontario, in the State of New York, have invented new and useful 5 Improvements in Sash-Locks, of which the following, taken in connection with the accompanying drawings, is a full, clear, and exact description.

My invention relates to devices for locking 10 window-sash either when closed or when raised or lowered, and which is mortised into the edge of a sash, engages with a rack in the stile of the casing, and is operated by a pin inserted through the sash, inside of the glass, 15 and connected to the locking device.

My object is to produce a lock easily manipulated and which can be set so that it can only be operated by releasing the locking mechanism from the set.

20 My invention consists in the several novel features of construction and operation hereinafter described, and which are specifically set forth in the claims hereto annexed. It is constructed as follows, reference being had to 25 the accompanying drawings, in which—

Figure 1 is a sectional elevation of a window casing, sash, and lock in position locking the sash. Fig. 2 is an elevation of the rack in the stile of the casing, showing the holes 30 bushed. Fig. 3 is a side elevation of the whole lock detached from the sash. Fig. 4 is a plan view of the edge of the sash with lock in position.

A is the window-casing.

35 B is a sash adapted to slide vertically in the casing and mortised at 1 to receive the locking-bolt 2. This bolt consists of a bar of metal pivotally mounted upon a pin 3 let into the sash, having one end of the stud or teat 40 4, which fits into one of the holes 5 in the stile of the casing, and in the other end of the bolt

I screw the threaded outer end 6 of the shifting-pin 7. When the sash is locked, the stud 4 is in one of the holes 5. Then by pushing the pin 7 inwardly the leverage throws the stud 45 out of engagement and unlocks the sash, so that it can be raised, (or lowered,) and when raised (or lowered) to the desired point the releasing of the pressure on the pin enables the spring 8 to throw the stud into another 50 hole in the rack. Then, when it is so locked, it can be set, so that the stud cannot be withdrawn, by screwing the screw 6 farther into the bolt until the end projects, as shown by the dotted lines in Fig. 3, and so that when 55 the pin 7 is pushed in, the end of the screw will strike the stile before the stud is withdrawn from the hole with which it is then engaged.

What I claim as my invention, and desire 60 to secure by Letters Patent, is—

1. The combination, with the sash and a rack in the stile of the casing, of a bolt pivoted in the sash-rail and engaging with the rack and a push-pin inserted through the 65 sash-rail and adapted to be screwed into and through one end of the bolt.

2. The combination, with a sash and a rack in the stile of the casing, of a bolt pivoted in the sash-rail and having a stud on one end 70 adapted to engage with the rack, a push-pin inserted through the sash-rail and adapted to be screwed into the free end of the bolt and project beyond it, and a spring behind the bolt to throw the stud into engagement with 75 the rack, as set forth,

In witness whereof I have hereunto set my hand this 12th day of February, 1890.

ROBERT I. TURCK.

In presence of—

H. P. DENISON,
BESSIE H. DENISON.
